UNITED STATES PATENT OFFICE.

MATTHEW A. RAFTERY AND OSCAR FREY, OF NEW YORK, N. Y.

ATTACHMENT FOR THE PROMOTION OF EASE AND SPEED IN WRITING.

1,173,607.

Specification of Letters Patent.

Patented Feb. 29, 1916.

Application filed March 15, 1912. Serial No. 683,959.

To all whom it may concern:

Be it known that we, MATTHEW A. RAFTERY and OSCAR FREY, citizens of the United States, and residents of New York, in the county and State of New York, have invented a new and useful Improvement in Attachments for the Promotion of Ease and Speed in Writing, of which the following is a full, clear, and exact specification.

10 The object of our invention is to make easy of attainment in writers a smooth, swift, gliding movement of the hand and arm which is conducive to speed in writing.

Another object of our invention is to obviate the frictional contact of the hand, or one or more of the fingers thereof, with the writing material.

20 A further object of the invention is to provide a movable rest for the hand which, while facilitating the acquirement of speedy writing, at the same time secures the steady effect usually imparted by resting one or more fingers on the paper or writing material, but without the retardation resulting from the latter practice.

It is generally recognized that the better system of writing is that which consists in having the movement of the hand controlled by the upper part of the arm, from the shoulder to the elbow, rather than from the wrist, the hand being positioned so as not to touch the writing material, but being supported by the fleshy part of the forearm or muscle near the elbow, thereby making it unnecessary to rest anything more than one or two of the fingers on the writing material. Our invention is adapted to bring about the ready adoption of this system by means hereinafter described.

40 Our invention resides in a device to be fastened usually to one of the fingers of the writer, consisting in combination, of attaching and resting means, and a ball bearing or polished sphere or smooth piece of metal or other material, which comes in contact with the writing material.

Referring to the accompanying drawings forming part of this specification, and in which similar reference characters indicate corresponding parts in the different views, Figure 1 is a perspective view of our device in position; Fig. 2 is an elevation thereof; Fig. 3 is a plan view of our invention; and Figs. 4 and 5 are modifications of the same. 55 Fig. 6 is a longitudinal section of the ball and socket shown in Fig. 2.

Referring to Fig. 1, the attaching means consists of annular bands 1 and 2, connected by a longitudinal strip 3. Attached to the lower annular band is a ball-bearing or 60 polished sphere of metal, or other material, 4. Projecting from the lower band in the direction of the other fingers is a flange 5. In this illustration our device is attached to the fourth or small finger of the hand, 65 although in some cases, depending upon individual needs, the user may prefer to use it on the second or third finger. In this figure the third finger is resting upon the flange 5. It will be evident that as the writer proceeds 70 with his work the part 4 will be the only portion of the device coming in contact with the writing material, the ball bearing being thus caused to revolve quickly with the movement of the hand, or the polished 75 sphere, or piece of metal, to glide swiftly over the said material. Our invention therefore compels the adoption of the proper hand and arm movement needful for speedy and easy writing. It also does away with the 80 friction arising from contact of the fingers with the paper, especially where the fingers are slightly moist from perspiration.

Fig. 2 illustrates in elevation the same parts shown in Fig. 1.

In Fig. 3, which is a plan view of the device, the annular band 1 is shown as somewhat smaller in circumference than the upper band 2, which is our usual method of construction. These partly open annular 90 bands we prefer to make of flexible metal so that when attached to a finger of the user they may be clasped as tightly around the same as may be desired, and can be easily removed. The flange 5 is also preferably 95 made of flexible metal to facilitate ease of adjustment to any desired angle. The longitudinal strip connecting the bands we prefer to make of some rigid material, preferably metal. The upper annular band, however, may also be made of some elastic material, as shown in Fig. 4 at 6.

In the modification illustrated in Fig. 5 we show the invention as consisting of one partly open annular band of about the width 105 sufficient to cover the lower joint of one of the fingers. This modification we prefer to make of flexible metal, and part of one side of it is lengthened so as to curve under the finger on which the attachment is placed. 110 In the under side of this extension is located the ball bearing or polished piece of

metal 4. The extension being flexible, can be adjusted by the user to any desired angle. On the side of the device which is lengthened in part to form this extension is placed the 5 flange or rest 5 for another finger. This rest imparts added steadiness to the device in use although not altogether necessary, and it may be dispensed with without materially lessening the advantages of our improvement. On the opposite side of this modification is a concave surface 7, against which the adjacent finger bears.

While we have described our invention in detail we do not limit ourselves to such details. Our device, and the parts of same, can of course be made of various kinds of materials and in different shapes and sizes to meet all requirements. If desired more than one ball bearing could also be attached 20 to our improvement, or the same made adjustable to suit individual requirements. It is also evident that while we have described our invention as intended for users of pen or pencil, it could also be attached to the 25 tools and implements of other trades and arts where lightness and freedom of movement are essential. Our invention will be found of great help to stenographers in speedy reporting and to students and users 30 of the Palmer method of writing.

What we claim as new and desire to secure by Letters Patent, is:

1. An attachment for promoting speed in writing comprising supporting means for 35 the hand adapted to be attached to one of the fingers, and provided with a support for the next adjacent finger, said supporting means contacting with the writing surface when in use.

40 2. A device of the character described provided with a member adapted to encircle the finger, a member projecting outward therefrom and adapted to act as a support for the next adjacent finger, means contacting with 45 the writing surface when in use, said means being arranged opposite the projecting member.

3. A device of the character described provided with parallel bands adapted to encircle 50 one of the fingers, a member connect-

ing said bands, a member projecting outward therefrom adapted to engage with the next adjacent finger, said member being in a plane substantially horizontal to said connecting member, and means contacting with the writing surface when the device is in use.

4. A device of the character described provided with parallel bands adapted to encircle one of the fingers, a member connecting said bands, a member projecting outward therefrom adapted to engage with the next adjacent finger, said member being in a plane substantially horizontal to said connecting member, and means mounted on 65 one of said parallel bands opposite the said projecting member, said means contacting with the writing surface when the device is in use.

5. A device of the character described provided with parallel bands adapted to encircle one of the fingers, a member connecting said bands, a member projecting outward therefrom adapted to engage with the next adjacent finger, said member being in a plane substantially horizontal to said connecting member, and a ball bearing mounted on one of said parallel bands opposite the said projecting member, said ball bearing contacting with the writing surface 80 when the device is in use.

6. A finger attachment for promoting ease and speed in writing consisting of a flexible annular band of metal to which is attached a ball bearing projecting from said band, a finger rest projecting outwardly from said annular band opposite said ball bearing, and an elastic encircling band above, and attached to, said annular band by a strip of rigid material, said ball bearing contacting with the writing surface 90 when the device is in use.

In testimony whereof, we have signed our names to this specification, in the presence of two subscribing witnesses.

MATTHEW A. RAFTERY.
OSCAR FREY.
